UNITED STATES PATENT OFFICE

2,010,604

REFRIGERATOR

Boynton K. Miller, Fond du Lac, Wis., assignor to Sanitary Refrigerator Company, Fond du Lac, Wis., a corporation of Wisconsin

Application January 17, 1935, Serial No. 2,264

4 Claims. (Cl. 62—46)

The invention aims to improve upon the construction disclosed by U. S. patent to William Mauthe, No. 1,958,832, May 15, 1934, by the provision of a novel structure allowing less obstructed circulation of air.

With the foregoing in view, the invention resides in the novel subject matter hereinafter described and claimed, description being accomplished by reference to the accompanying drawings, wherein:

Fig. 1 is a vertical sectional view cut in a plane at right angles to the refrigerator front.

Fig. 2 is a horizontal sectional view on line 2—2 of Fig. 1.

Fig. 3 is a front elevation with the ice chamber and food chamber doors removed, parts of this view being shown in vertical section on the plane of line 3—3 of Fig. 1.

Fig. 4 is a detail sectional perspective view of the construction shown at the left of Fig. 1.

A preferred construction has been shown and will be specifically described, with the understanding however, that minor variations may be made within the scope of the invention as claimed.

An appropriate insulating casing C is shown, provided with a lower door D into a food chamber F and with an upper door D' into an ice chamber I. The two chambers are separated by a partition 10 which preferably declines slightly toward the rear end in which a drain 11 is located. The partition 10 is provided with an upwardly directed front portion 12 which is rearwardly spaced from the dividing rail R between the upper and lower doors D and D', said upwardly directed portion being provided with a multiplicity of air-conducting openings 13. The upper edge of the portion 12 is bent forwardly to provide a flange 13^a which is riveted or otherwise secured upon a plurality of horizontally spaced brackets 14 which are in turn secured to the rail R, said brackets serving to space the flange 13^a rearwardly from said rail R, and to support said flange and the connected portion 12. The back edge and the front-to-rear edges of the partition 10 are fluid-tightly secured to the refrigerator lining 15, the spacing of the flange 13^a at the front of said partition from the rail R, however, permitting the ascent of relatively warm air from the front portion of the food chamber F into the front portion of the ice chamber I.

A cowl 16 extends over the openings 13 to prevent any drip water or water of condensation from flowing down the wall portion 12 through

said openings into the food chamber F. This cowl 16 may well be formed by rearwardly and downwardly bending the lower edge of a vertical sheet metal plate 17 whose upper edge is secured at 18 to the rearwardly projecting sill 19 of the upper door frame. The plate or wall 17 is rearwardly spaced from the rail R, providing an air conducting passage 20 between them. This passage receives the air ascending in front of the wall portion 12, and an escape slot 21 is provided in the wall or plate 17 to allow this ascending air to enter the ice chamber I, at the front portion of the latter.

An ice supporting rack 22 is provided, substantially identical with the ice rack shown by the patent above mentioned, said ice rack being formed from a corrugated plate to provide it with a plurality of downwardly open channels 22^a and a plurality of upwardly open channels 22^b, all of said channels being open at their ends. The front end of the rack 22 may well rest upon the cowl 16 which is of course solidly supported by the flange 13^a and the brackets 14, and an appropriate ledge or the like 23 is employed to support the rear end of said rack. Secured to the lower side of the rack 22, I have shown shielding means 24 extending over air circulation openings 25 which are formed through the partition 10. The shielding means 24 prevents any water dripping from the rack 22 directly through the openings 25, and to prevent water flowing down the upper side of the partition 10 from passing through the openings 25, protecting flanges 26 are provided around said openings.

The upwardly flowing relatively warm air in the front portion of the ice chamber I, after reaching the upper portion of this chamber, flows rearwardly, downwardly behind the ice block B, and downwardly at opposite sides of the latter, said air passing through openings 27 in the bottoms of the channels 22^b and also through openings number 30 on either side of the ice rack, and also may pass behind ice cake through openings 22^a and then descending through the openings 25 into the rear portion of the food chamber F. Rearward sliding of the block B against the rear wall of the refrigerator is prevented by a vertical guard rack 28 which may be spaced from said rear wall by means of vertical spacing bars 29, the space between the rack 28 and said rear wall constituting an air conducting passage through which the air may descend behind the ice block. This air flows downwardly and forwardly through the openings 22^a and 27 into the space between the rack 22 and the partition 10.

and while most of this air descends through the openings 25, the least chilled naturally has a tendency to short-circuit to the ascending air. It, therefore, flows forwardly through the openings 13 and is entrained with the ascending air flowing to the front portion of the ice chamber I from the corresponding portion of the food chamber F, through the passage 20 and the slot 21. No drippings from the ice block B can reach the portion of the plate or wall 17 in the vicinity of the slot 21 and hence it is not necessary to provide any means over this slot to prevent such drippings from flowing therethrough into the food chamber. 15 By providing the novel construction shown and described or a substantial equivalent thereof, an improved refrigerator is produced in which air circulation can much more freely take place than in the patent above mentioned. While the 20 details disclosed are preferred, attention is again invited to the possibility of making variations within the scope of the invention as claimed.

I claim:

1. A refrigerator comprising a casing having a 25 partition dividing it into an upper ice chamber and a lower food chamber, said partition having an opening through which air may descend from said ice chamber, said casing being provided with upper and lower doors into said ice and food 30 chambers respectively and with a dividing rail between said doors, a sill for the upper door projecting rearwardly from said dividing rail, a vertical wall secured to said sill and projecting downwardly therefrom in rearwardly spaced relation with said dividing rail, said wall having an air conducting opening through which ascending air may pass, the lower edge portion of said wall being directed rearwardly and downwardly to provide a cowl, an additional vertical wall rising 40 from the front end of said partition and terminating under said cowl, and brackets supporting the upper edge of this wall, said brackets being secured to said dividing rail and spacing said upper edge of the last mentioned wall rearwardly from said rail, said last mentioned wall having an opening through which air may flow forwardly.

2. A refrigerator comprising a casing, a partition dividing said casing into an upper ice 50 chamber and a lower food chamber, said partition having an opening through which air may descend, said casing being provided with upper and lower doors into said ice and food chambers respectively, and having a dividing rail between said doors, the front edge of said partition being provided with an upwardly projecting wall spaced rearwardly from said rail and having an opening through which air may flow forwardly, a cowl extending over said opening to

5 prevent drip water from passing therethrough, a second vertical wall carrying said cowl and extending upwardly from the first named wall in rearwardly spaced relation with said dividing rail, and means securing the upper edge of said second wall to said dividing rail, said second wall having an opening through which ascending air may flow rearwardly.

3. A refrigerator comprising a casing, a partition dividing said casing into an upper ice chamber and a lower food chamber, said partition having an opening through which air may descend, said casing being provided with upper and lower doors into said ice and food chambers respectively and having a dividing rail between said doors, the front edge portion of said partition being rearwardly spaced from said dividing rail and having an upstanding wall formed with an opening through which air may flow, the upper edge of said wall being provided with a forwardly projecting flange which also is spaced rearwardly from said dividing rail, brackets upon which said flange is secured, said brackets being secured to said dividing rail, a cowl overlying said flange and 25 extending downwardly at the rear of the aforesaid wall to prevent drip water from flowing through said opening, and a second vertical wall carrying said cowl and rising therefrom, the upper edge portion of said second wall being secured to said dividing rail, said second wall having an opening through which ascending air may enter the ice chamber.

4. A refrigerator comprising a casing, a partition dividing said casing into an upper ice chamber and a lower food chamber, said partition having an opening through which air may descend, said casing being provided with upper and lower doors into said ice and food chambers respectively and having a dividing rail between said doors, the front edge portion of said partition being rearwardly spaced from said dividing rail and having an upstanding wall formed with an opening through which air may flow, the upper edge of said wall being provided with a forwardly projecting flange which also is spaced rearwardly from said dividing rail, brackets upon which said flange is secured, said brackets being secured to said dividing rail, a cowl overlying said flange and extending downwardly at the rear of the aforesaid wall to prevent drip water from flowing through said opening, and a second vertical wall carrying said cowl and rising therefrom, and a sill for the upper door, said sill being secured to and projecting rearwardly from said rail, the upper edge portion of said second wall being secured to said sill, said second wall having an opening through which ascending air may enter the ice chamber.

BOYNTON K. MILLER.
